CLAIM

The ornamental design for an oral irrigator medicament reservoir, as shown and described.

DESCRIPTION

FIG. 1 is an isometric view of an oral irrigator medicament reservoir showing our new design.

FIG. 2 is a top plan view thereof, with the top plan view of the second embodiment shown in FIGS. 9–15 being identical thereto.

FIG. 3 is a front elevation view thereof.

FIG. 4 is a left side elevation view thereof.

FIG. 5 is a right side elevation view thereof.

FIG. 6 is a bottom plan view thereof.

FIG. 7 is a rear elevation view thereof.

FIG. 8 is an exploded isometric view thereof.

FIG. 9 is an isometric view of a second embodiment of an oral irrigator medicament reservoir, showing our new design.

FIG. 10 is a front elevation view thereof.

FIG. 11 is a left side elevation view thereof.

FIG. 12 is a right side elevation view thereof.

FIG. 13 is a bottom plan view thereof.

FIG. 14 is a rear elevation view thereof; and,

FIG. 15 is an exploded isometric view thereof.
